TRANSPARENCY VIEWING APPARATUS

Louis Pasternack, Northbrook, Ill. (% Western Blue
Print Co., 2415 W. Peterson Ave., Chicago 12, Ill.)

Filed Mar. 23, 1959, Ser. No. 55,139

Term of patent 3½ years

(Cl. D61—1)

FIG. 4

FIG. 5

Fig. 1 is a perspective view of a transparency viewing apparatus embodying my new design;

Fig. 2 is a front elevational view to a reduced scale;

Fig. 3 is a rear elevational view to a reduced scale;

Fig. 4 is a side elevational view with the base extended, the opposite side being substantially a mirror image thereof; and

Fig. 5 is a top plan view thereof.

The broken line showing of a film projector is for illustrative purposes only.

I claim:

The ornamental design for a transparency viewing apparatus, substantially as shown and described.
